[57] CLAIM

The ornamental design for a compact electronic scanner, as shown and described.

DESCRIPTION

FIG. 1 is a right side elevational view of a compact electronic scanner showing my new design, the left side being a mirror image of the right side;

FIG. 2 is a top plan view thereof;

FIG. 3 is a top, right side perspective view thereof on a reduced scale;

FIG. 4 is a front elevational view thereof; and

FIG. 5 is a rear elevational view thereof;

The bottom is plain and unadorned.

FIG.1

FIG.2

FIG.3

FIG.4
